DEVICE FOR HANDLING SHEET MATERIAL

Edward V. Grater, Bronx, N. Y., assignor to Affiliated Machine & Tool Co., New York, N. Y., a partnership

Application June 14, 1947, Serial No. 754,787

3 Claims. (Cl. 294—1)

1

This invention relates to means for handling sheet material such as metal, glass, plastic, etc.

In the fabrication of articles from sheet material it is often necessary for workmen to grasp the said material by its edges. This practice has resulted in many industrial hand injuries despite the use of gloves and other protective devices. Where rags or waste are employed to protect the hands of the worker, they have frequently become entangled in moving machinery, resulting in more serious accidents.

Accordingly, it is an object of this invention to provide a safe means for handling sheet material.

Another object of this invention is to provide a handling device capable of facilitating the feeding sheet material into a machine.

A further object of this invention is to provide a device for feeding sheet metal into a machine having means therein to reverse the direction of the said feed.

An object of this invention is to provide a device for handling a wide variety of thicknesses of sheet material, without the requirement of adjustment.

A feature of this invention is the use of an eccentrically mounted cam to grasp the edge of the sheet material.

Another feature of this invention is the use of a coil spring to urge the cam into contact with the sheet material.

A further feature of this invention is its simplicity of construction.

The invention consists of the construction, combination and arrangement of parts, as herein illustrated, described and claimed.

In the accompanying drawings, forming a part hereof, is illustrated one form of embodiment of the invention, in which drawings similar reference characters designate corresponding parts, and in which:

Figure 1 is a view in elevation of a complete embodiment of the invention, partially cut away to show its construction.

Figure 2 is a sectional view taken on line 2—2 of Figure 1, looking in the direction indicated by the arrows.

Figure 3 is an end view in elevation of the invention.

Figure 4 is a fragmentary view of the cam receiving recess showing the position of the coil spring therein.

Figure 5 is a rear view of the cam.

Figure 6 is a side elevation of the cam.

Referring to the drawings, and particularly to

10

Figures 1 through 3, 10 indicates a handle shaped housing having an arched central portion 11 and upstanding end members 12 to prevent hand slippage. The housing 10 is centrally recessed at 13. The recess 13 is circular in shape except for the bottom portion thereof, which is cut off by the bottom 14 of the housing 10 at 15.

15

A central bore 16 is provided in the rear wall 17 of the recess 12. The wall 17 is also provided with an annular groove 18 concentric with the bore 16. This groove 18, best shown in Figures 2 and 4, is provided with a pin 19 located in its uppermost part. The upper portion of the pin 19 has a diameter equal to the width of the groove 18 into which it projects.

20

A coil spring 20 is positioned within the groove 18 and is slightly shorter than the length of said groove. One end 21 of the coil spring 20 bears against the pin 19, while the other end 22 of the spring is spaced from the said pin (see Figure 4). It is possible to shift the spring 20 so that its end 22 bears against the pin 19 and its end 21 is spaced therefrom. This change will affect the operation of the handling device in a hereinafter described manner.

25

The cam 23, which comprises the sole moving part of this invention, is best shown in Figures 5 and 6. This cam 23 is circular in shape and provided with an eccentrically located bore 24. It is provided with a pin 25 press-fitted into but projecting from the rear face 26 thereof. The front face 27 of the cam 23 is beveled at 28. A knurl 29 is machined into the periphery of the cam 23 and also into the bevel 28. This knurl 29 prevents the cam 23 from slipping as it grips the sheet material.

30

The cam 23 is supported by a bolt 30 which is inserted through the bore 16 of the main housing 10. This bore 16 may be enlarged toward its outer end, as shown at 31 in Figure 2, to receive the head of the bolt 30. The bolt 30 is passed through the eccentrically located bore 24 of the cam 23 and screws into the threaded bore 32 of a plate 33.

35

The plate 33 is arcuate in shape and seats within a lip 34 cut into the main housing 10 around the edge of the recess 13 in such manner that the plate 33 lies flush with the front of the housing 10. The bottom 35 of the plate 33 is straight and conforms to the bottom 14 of the housing 10.

40

A gripping flange 36, having an L-shaped cross-section shown in Figures 1 to 4 is secured to the bottom of the housing 10 as by screws 37. The base of this flanged member 36 is recessed

to receive the screws 37 so that a smooth surface will result along the bottom of the handling device. The horizontally extending portion 38 of the L-shaped gripping flange underlies the cam 23 and, in conjunction with the base of the housing 10, forms a channel 40 through which the edge of the sheet material (not shown) may pass.

When the cam 23 is slipped upon the bolt 30 the pin 25 projecting from the said cam is fitted into the groove 18 between the pin 19 and the end 22 of the spring 20 (see Figure 4). The coil spring 20 thus opposes any rotating of the cam 23 upon the bolt 30. This action keeps the cam 23 in contact with the sheet material at all times. The preferred construction of this device shown in the drawings contemplates a positioning of the cam bore 24 and pin 25, which will give the cam an 18° offset from the vertical before the sheet material is introduced into the channel 40.

The operation of the handling device becomes apparent from an examination of Figures 1 to 3. The edge of the sheet material is slipped into the channel shaped groove 40 formed by the bottom 14 of the housing 10 and the gripping flange member 36. The handling device is then drawn back or in a direction opposite the direction of feed. As the edge of the material rubs along the bevel 28 of the cam 23, the knurl 29 thereon causes the cam 23 to rotate upon the bolt 30. This rotation causes the bevel to climb up the edge of the material, which lifts the cam 23 so that the sheet material can slide beneath it. Once the sheet material is within the channel 40 it may be pulled or fed in only one direction, any motion in the opposite direction being resisted by the construction of the cam 23 which will turn upon the bolt 30 and force the sheet material against the gripping flange member 36. The knurled teeth 29 on the surface of the cam 23 prevent the sheet material from slipping past the said cam 23.

In order to reverse the direction of feed of the handling device, it is only necessary to unscrew the bolt 30, remove the plate 33, push the coil 45 spring 20 around the groove 18 as described above, and reassemble the device with the cam pin 25 on the opposite side of the pin 19 in the groove 18.

While the cam 23 shown in the drawings is disclosed as metal, it is within the purview of this invention to construct it of resilient material or with a resilient face to handle materials such as glass or ceramics.

The construction of this device will enable the

user to grasp sheet material of various thicknesses from several thousandths of an inch up to the width of the channel 40, without making any adjustment of the handling device.

Having thus fully described the invention, what is claimed as new and desired to be secured by Letters Patent of the United States is:

1. In a device for handling sheet material, a housing, an eccentrically bored cam comprising a circular member provided with a bevel on the front edge thereof adapted to raise the cam mounted within the housing, a gripping plate thereunder secured to the housing and means to urge the cam against the said gripping plate.
- 15 2. In a device for handling sheet material, a housing, a recess within the housing having an axially bored rear wall provided with an annular groove, a pin located within the said groove, an eccentrically bored cam mounted within the recess, said cam having a rearwardly projecting pin adapted to enter the annular groove and a bevel on the front face thereof adapted to raise the cam, a gripping plate thereunder secured to the housing and means positioned within the 20 annular groove to urge the cam against the said gripping plate.
- 25 3. In a device for handling sheet material, a housing, a recess within the housing having an axially bored rear wall provided with an annular groove, a pin located within the said groove, an eccentrically bored cam mounted within the recess, said cam having a rearwardly projecting pin adapted to enter the annular groove and a bevel on the front face thereof adapted to raise the cam, a gripping plate thereunder secured to the housing and spring means positioned within the 30 annular groove between the two pins therein to urge the cam against the said gripping plate.

EDWARD V. GRATER.
